UNITED STATES PATENT OFFICE.

HERMAN MATERN, OF ALBANY, NEW YORK.

COIN-CONTROLLED GAME APPARATUS.

SPECIFICATION forming part of Letters Patent No. 518,617, dated April 24, 1894.

Application filed December 28, 1893. Serial No. 494,980. (No model.)

To all whom it may concern:

Be it known that I, HERMAN MATERN, a subject of the Emperor of Germany, residing at Albany, in the county of Albany and State 5 of New York, have invented new and useful Improvements in Coin-Controlled Game Apparatus, of which the following is a specification.

My invention relates to improvements in 10 coin-controlled game-apparatus, and it consists of the novel construction and arrangement of parts shown in the drawings, described in this specification, and pointed out in the claims.

15 In the accompanying drawings, which are herein referred to and form part of this specification, Figure 1 is a front elevation of my invention inclosed in its casing. Fig. 2 is a rear elevation of the same. Fig. 3 is an enlarged front elevation, with the front of the casing removed, and part of the framing broken out, to show underlying parts. Fig. 4 is a sectional detail showing the manner of locking the two parts of the number wheel together. 25 Fig. 5 is an enlarged rear elevation, with the door of the casing removed, and parts of the framing broken out. Fig. 6 is an enlarged end elevation, with the end of the casing removed. Fig. 7 is an enlarged partial horizontal section of Fig. 6 at the line Y Y; and 30 Fig. 8 is an enlarged partial vertical section of Fig. 5 at the line X X.

As represented in the drawings, A designates a casing for inclosing my invention; 35 said casing having in its rearmost side an opening which is closed by a door, 1, and through which access can be obtained to the operative parts of the apparatus. A drawer, 2, is placed in the lower part of the casing A 40 for the purpose of receiving the coins used for operating the apparatus.

B designates a ticket-wheel that is provided with a series of radially-arranged slots, 3, formed near the periphery of the wheel 45 and are open through both sides of the latter, so that a suitable ticket, when inserted in either of said slots, will project from the opposite faces of the wheel. The wheel B is fitted to rotate loosely on a spindle, 4, which 50 normally remains in a fixed position; a ratchet-wheel, 5, secured to said spindle, and a pawl, 6, is arranged to take into the teeth of

said ratchet-wheel to prevent said spindle from being rotated in a wrong direction. A volute-spring, 7, having one end secured to 55 the spindle 4 and the opposite end attached to a stud, 8, in the side of the wheel B, is provided for imparting a rotary motion to said wheel in the manner hereinafter described. A series of spurs, 9, is arranged around the 60 periphery of the wheel B in position to correspond with the slots 3, and a second series of spurs, 10, positioned intermediately to the spurs 9, is arranged independently of the latter around the periphery. The slots 3 and 65 spurs 9 are omitted, as at 11, from one portion of the wheel B for a purpose hereinafter explained. The spindle 4 is journaled in a stationary frame, 12, which also carries other 70 parts of the apparatus.

C designates a sliding-bar that is arranged beneath the wheel B and is provided with a standing-flange, 13, arranged to engage alternately with the spurs 9 and 10 of said wheel; one end of said sliding-bar projects through 75 the front of the casing A and is provided with a knob, 14, or other means for imparting a sliding motion to said bar; the inner end of said sliding-bar is bifurcated to form limbs, 15, which are connected by a cross-bar, 16, to 80 form an opening, 17, for a purpose hereinafter explained.

D designates a tilting-lever, fulcrumed at 18, and having a counterweight receptacle, 19, pivoted to one end of it in such manner 85 that said receptacle can be maintained in a vertical position to bring a counterweight, 20, directly under the pivots of said receptacle, and said counter-weight is usually a coin corresponding to the coin used for controlling 90 the operation of the apparatus. The tilting-lever D carries, on the end opposite to the receptacle 19, a receiver, 21, for the coin for operating the apparatus; said receiver is provided with an end, 22, which is pivoted to 95 said receiver, as at 23, to adjust said end, in respect to the opening through the bottom of the receiver, to adapt the latter for retaining coins of different values. An adjusting-screw, 24, is jointed to said end, and passes through 100 a slotted opening in a standard, 25, and is provided with a nut, 26, that bears against the face of said standard to limit the movement of the end 22 in one direction. A spring,

- 27, is arranged to bear against the end 22 to normally keep the nut 26 bearing against the standard 25. Jointed to the lower end of the end 22, is a link, 28, having a slotted opening, 29, in which an arm, 30, extending laterally from the sliding-bar C, engages in such manner that a sliding movement of said bar toward the front of the apparatus will cause the arm 30 to take against the forward end 10 of the slotted opening 29 and effect a swinging movement of the end 22 to increase the opening through the lower side of the receiver 21 to a sufficient degree to allow the coin to fall from said receiver. An opening, 31, formed directly beneath the receiver 21, through the horizontal partition, 32, allows the coin discharged from the receiver to fall into the drawer 2; when the strain on the link 28 is released, the resilience of the spring 27 15 will force the end 22 back to the position it was in before it was swung to increase the capacity of the opening through the bottom of the receiver 21. The latter can have a graduated scale marked thereon, as shown 20 in Fig. 8, to indicate the required position of the end 22 to suit coins of different values. With a counterweight, 20, in the receptacle 19, the tilting-lever D will normally remain in a horizontal position, as shown in Fig. 8, 25 until a coin of the required weight to overcome the effect of the counter-weight is dropped into the receiver 21, whereupon said lever will be tilted, as indicated by dotted lines in said figure, until the coin is discharged from said receiver, and then said lever will tilt back to its normal position.
- Attached to the receiver-end of the tilting-lever D, is a plate or arm, 33, having a vertical flange, 34, of sufficient length to enter the 30 opening 17 and prevent the sliding movement of the sliding-bar C, but, by the tilting down of the receiver-end of the tilting-lever D, said flange is swung out of said opening and thereby the sliding-bar is released from the control of said flange and is left free to be drawn forward against the resistance of a spring, 35, which, when the strain is removed from the sliding-bar C, will restore the latter to its 35 normal position.
- 30 E designates a vertical arm that is erected on the upper face of the sliding-bar C and is arranged to move along the face of a plate, 36, attached to the frame 12; said plate being arranged in position to have one end of the tickets, held in the slots 3, come in contact with the face of the plate 36, so as to lie in the path of the arm E, and, by an outwardly-sliding movement of the bar C, the arm E will push the ticket, with which it is 40 in contact, partially through the slot in which it is contained and so that the foremost end of said ticket will project from a slotted opening, 38, formed in the front of the casing A, wherefrom it can be drawn by hand. A plate, 37, is secured to the forward leg of the frame 12, so as to range in line with the plate 36 which is attached to the other leg of said

frame, and ranging in line with one side of the opening 38, so as to form a guide for the tickets into said opening. A guard, 39, is 70 hinged to the frame 12 and is arranged to keep the opening 38 closed while the sliding-bar C remains in its normal position; said guard is provided with an arm, 40, which takes against a shoulder of said sliding-bar 75 in such manner that a forward movement of the latter will swing said guard to open the opening 38, as indicated by dotted lines in Fig. 7; a spring, 41, arranged to bear against the arm 40, keeps the guard 39 in position to 80 close the opening 38 during the time the sliding-bar C is at the inner termination of its movement, and said guard, by closing the opening 38, prevents access to the tickets in the slots 3 when the apparatus is not properly operated.

F designates a duplex number-wheel, consisting of a disk, 42, secured to a shaft, 43, and having on its front a consecutive series of numbers, corresponding to the number of 90 slots 3 in the wheel B, arranged on a circular line and spaced at regular intervals; on the rear of said disk a series of consecutive numbers, equal to one half of the numbers on the front of said disk, is arranged so that corresponding numbers on both sides of the disk 95 will occupy corresponding places.

In front of the disk 42, a supplemental disk, 44, is arranged to move loosely on the shaft 43; said supplemental disk is provided with 100 a series of numbers corresponding to the first half of the series of numbers on the front of the disk 42. A segmental portion is removed from the periphery of the supplemental disk so that—when the two disks are arranged correspondingly—either a series of consecutive 105 numbers equal to the number of the slots 3 can be shown on the combined faces of the two disks, or two series of a lesser number can be shown on the combined faces, and a locking device, 45, is provided for holding the disks 42 and 44 in the position in which they have been adjusted. In order to balance the supplementary disk 44, an opening, 46, is formed therein opposite to the place where 110 the segmental portion has been removed.

The periphery of the duplex number-wheel F is provided with a series of notches, 47, corresponding in number and location to the full series of numbers on the disk 42, and a delicate spring-detent, 48, is arranged to bear 115 against the periphery of said wheel with sufficient friction to prevent said wheel from running wild when released in the manner described herein; said detent is also adapted to engage lightly in either of said notches that is opposite to the lip of the same when the wheel is brought to a stop. A spring, 49, has one end fastened to the frame 50, or other fixed point conveniently located, and the opposite end of said spring is connected to the shaft 43 for the purpose of imparting a rotatory motion to the latter; as shown in the drawings, said spring is made in the form of 120

a spiral and is connected to the shaft 43 by means of a belt, 51, but when preferred the entire spring may be made of an elastic belt which can be wound around said shaft in the manner shown, in respect to the belt 51, in Fig. 5. When the shaft 43 is released from the hold of its controlling mechanism, as hereinafter explained, the resilience of the spring 49 will cause the wheel F to be rotated in the direction indicated by the arrow marked on said wheel in Fig. 5. A ratchet-wheel, 52, is secured to the shaft 43, and a lever, 53, fulcrumed, at 54, is provided with a detent, 55, fitted to take against the teeth of said ratchet-wheel and hold the shaft 43 from being rotated by the spring 49; the opposite end of the lever 53 is provided with a cam-shaped projection, 56, arranged to lie in the path of movement of a stud, 57, fixed in the side of the wheel B, so that, when said wheel is rotated into the required position, said stud will take against the projection 56 and depress the detent end of the lever 53 from the ratchet-wheel 52, thereby releasing the shaft 43 from the control of said detent, and allowing the spring 49 to rotate said shaft and the attached number-wheel until stopped by the friction of the detent 48.

Attached to the detent 55, is an arm, 58, which bends around the periphery of the number-wheel F and forms a shutter, 59, which, when the lever 53 is in its normal position, will be interposed between an opening, 60, in the front of the casing A, and the numbers on the number-wheel F, but, when the lever 53 is tilted, to release its detent from the ratchet-wheel 52, said shutter will be thereby carried from a position to close said opening, and the number on said number-wheel that is exposed through said opening will be the "winning-number," and the ticket bearing a corresponding number will become the "winning ticket."

G designates a chute through which the coin passes to be deposited in the receiver 21, and said chute is provided with a mouth-piece, 61, that is preferably bent at an angle to the line of the passage through said chute, so that the external orifice of said mouth-piece will be inclined rearwardly from the top of the casing A. For the purpose of adjusting said orifice to suit the different diameters of the coins used for operating my apparatus, an adjustable screw, 62, is inserted in said mouth-piece and is arranged to be manipulated from the interior of the casing A, so that it cannot be tampered with from the outside of said casing.

H designates the tickets which are inserted in the slots of the wheel B, and are made sufficiently long to protrude from each side of said wheel. Each of said tickets should bear a number that will correspond to a number on the number-wheel F, and the numbers should be successive, but the tickets need not be inserted in the slots 3 so that their numbers will be in regular rotation.

My apparatus is operated in the following manner: A counter-weight, 20, is deposited in the receptacle 21 to correspond to the weight of a coin required to operate the apparatus; if said receptacle contains a coin of a different weight, the coin is removed by turning over said receptacle and allowing the coin to drop therefrom through an opening, 63, into the drawer 2. Tickets H are inserted into the slots 3, or into as many of said slots as will correspond to the exposed numbers on the face of the disk 42. The spindle 4 is then turned—by a key or other implement—to wind up the spring 7; the shaft 43 is also turned in like manner to wind up the belt 51, and the apparatus will be in condition for operating. A coin of the required weight is then dropped into the chute G and, by falling into the receiver 21, tilts the lever D to carry the flange 34 out of the opening 17 and leave the sliding-bar C free to be slid forward. The wheel B, is held in a stationary position by a spur 9 bearing against the standing-flange 13, and by the ticket H—then ready for ejection from the wheel B bearing against the plates 36 and 37, the sliding-bar C is then pulled outwardly to push the ticket—by means of the arm E—partially from its slot in the wheel 95 B, so that the outer end of said ticket will project from the face of the casing A, as indicated by dotted lines in Fig. 6. The ticket is then drawn from the apparatus by hand, and the engaged stud 9 will pass by the inner end of the flange 13, and the wheel B—under the strain of the spring 7—will make a partial revolution to bring the succeeding stud 10 into contact with the flange 13, thereby causing another pause in the movement of the wheel B until the said spur passes the forward end of said flange and allows said wheel to make another partial revolution, whereby a succeeding spur 9 is brought into engagement with the flange 13; the inward movement of the sliding-bar C permitting the spur 10 to pass by the forward end of said flange to effect the last described movement of the wheel B. The forward movement of the sliding-bar C opens the passage in the bottom of the receiver 21, to allow the coin to drop from the latter, and thereby a preponderance of weight is given to the counter-weight 20 to restore the tilting-lever D to its normal position and effect the locking of the sliding-bar C in the manner previously described. When the wheel B has attained a point in its revolution where the last spur will pass clear of the flange 13 and bring the blank space 11 adjacently to said flange, the stud 57 will engage under the projection 56 and tilt the lever 53 in such manner that the detent 55 will be disengaged from the ratchet-wheel 52, thereby leaving the number-wheel F free to be rotated by the spring 49; said wheel will continue to rotate until its momentum is arrested by the detent 48. When the lever 53 is tilted, to release the number-wheel F, the shutter 59 will be moved to uncover the open-

ing 60, whereby the number then opposite said opening will be exposed at the front of the apparatus. After the stud 57 has passed by the projection 56 the lever 53 will tilt back into its normal position and the shaft 43 can again be wound up to allow the number-wheel to be operated in the manner just described.

What I claim as my invention, and desire to secure by Letters Patent, is—

1. A coin-controlled game apparatus, comprising a spring-actuated ticket-wheel, a spring-actuated number-wheel which is released to rotate by said ticket-wheel, a tilting-lever provided with a coin-receiver, and a sliding-bar that is normally locked by said tilting-lever; the releasement of said sliding-bar being effected by depositing a proper coin in said receiver, and said sliding-bar being provided with means—substantially as described—for interrupting the rotative movement of said ticket-wheel, as and for the purpose specified.
  2. The combination of a spring-actuated ticket-wheel provided with a series of slots for containing tickets and having two series of peripheral spurs arranged on different circumferential lines; one series of said spurs being arranged intermediately to the spurs of the other series, and a sliding-bar provided with a standing flange arranged to engage with said spurs successively; whereby the rotative movement of said ticket-wheel will be interrupted to effect a step-by-step rotation of said wheel, as and for the purpose specified.
  3. The combination of a spring-actuated number-wheel, a ratchet-wheel secured to the shaft which carries said number-wheel, a lever provided with a detent fitted to engage with said ratchet-wheel; said lever being also provided with a shutter which normally forms a closure for an opening in the casing of the apparatus, and a wheel provided with a stud arranged to effect a tilting movement of said lever; whereby said detent will be disengaged from the ratchet-wheel and the shutter moved from said opening, as and for the purpose specified.
  4. The combination of a tilting-lever carry-
- ing—at one end—a counter-weight receptacle which is pivoted thereto and is adapted to centralize a counter-weight directly under said pivot and—at the other end—having a coin-receiver provided with a swinging-end connected to an adjusting-screw for adapting said receiver for retaining different sizes of coins, and a sliding-bar that is normally locked by said tilting-lever and is connected to the swinging-end of the coin-receiver; whereby the apparatus can be adapted to be operated by coins of different sizes and weights, and the swinging-end of the coin-receiver be retracted to discharge the coin from said receiver, as and for the purpose specified.
5. In a coin-controlled game-apparatus, a number-wheel composed of a principal disk provided with a series of consecutively-arranged numerals, and a supplementary disk having a segmental portion of its surface removed to expose the numerals of the principal disk; said supplementary disk being provided with a lesser number of numerals than the principal disk, and a locking-device for securing the principal and supplementary disks together in such manner that said number-wheel will show either a continuous series of numerals, or two corresponding series of the same, as and for the purpose specified.
6. The combination of a casing provided with a ticket-discharge opening, a swinging-guard fitted to form a closure for said opening, a coin-controlled tilting-lever, and a sliding-bar normally locked in an immovable position by said tilting-lever and arranged to effect a movement of said guard to give free access to said opening, as and for the purpose specified.
7. In a coin-controlled apparatus, a coin-chute having its exterior opening provided with an adjustment manipulated from the interior of the casing of the apparatus; whereby said opening can be adjusted to prevent the introduction of a coin of too great a diameter into said chute, as herein specified.

HERMAN MATERN.
